ATTORNEY

UNITED STATES PATENT OFFICE.

EDWIN I. PYLE, OF BRIDGEPORT, CONNECTICUT, ASSIGNOR OF ONE-HALF
TO FRANK J. NARAMORE, OF SAME PLACE.

DESIGN FOR A GAME-BOARD.

SPECIFICATION forming part of Design No. 33,204, dated September 18, 1900.

Application filed August 15, 1900. Serial No. 26,994. Term of patent 3½ years.

To all whom it may concern:

Be it known that I, EDWIN I. PYLE, a citizen of the United States, residing at Bridgeport, in the county of Fairfield and State of Connecticut, have invented and produced a new and original Design for a Game-Board; and I do hereby declare the following to be a full, clear, and exact description of the invention, such as will enable others skilled in the art to which it appertains to make and use the same.

Referring to the accompanying drawings, Figure 1 is a plan view of my game-board, and Fig. 2 a section at the line $x-x$ of Fig. 1. 15 Similar numerals of reference denote like parts in both figures of the drawings.

The essential features of my newly-designed game-board are the centrally-located rectangular-shaped pen, having openings in the centers of two directly-opposite sides, and the four series of parallel vertical partitions outside of said pen and disposed in four planes, which are respectively at right angles to the four terminals of the diagonals of 20 said pen, the extremities of adjacent partitions of several series being separated by spaces.

It is further essential to my design that the

space between the two inner partitions of each adjacent series shall be equal to each other and also equal to the width of the openings in the sides of the pen, so that said spaces form lanes which lead directly to the closed sides of the pen in one instance, while in the other instance said spaces and openings form lanes which lead directly into the pen itself.

1 is the game-board proper, 2 the rectangular-shaped pen, and 3 the openings in the centers of the two directly-opposite sides thereof. 30 4 5 6 are the parallel vertical partitions.

7 are the lanes which lead between the two inner partitions of each adjacent series directly to the closed sides of the pen, and 8 are the lanes which lead between the ends of 35 these partitions in line with the openings 3 and directly into said pen.

I claim--

The design for a game-board, herein shown and described.

In testimony whereof I affix my signature in presence of two witnesses.

EDWIN I. PYLE.
